UNITED STATES PATENT OFFICE.

ALPHEUS W. MYERS, OF NEWARK, NEW JERSEY.

DESIGN FOR A SEWING-MACHINE COVER.

SPECIFICATION forming part of Design No. 15,094, dated June 24, 1884.

Application filed December 7, 1883. Term of patent 7 years.

To all whom it may concern:

Be it known that I, ALPHEUS W. MYERS, a citizen of the United States, residing at Newark, in the county of Essex and State of New Jersey, have invented a certain new and original Design for Sewing-Machine Covers; and I do hereby declare the following to be a full, clear, and exact description of the invention, such as will enable others skilled in the art to

10 which it appertains to make and use the same, reference being had to the accompanying drawings, and to letters of reference marked thereon, which form a part of this specification, in which—

15 Figure 1 is a side elevation, and Fig. 2 an end elevation, of my newly-designed cover, similar letters of reference being used to designate like parts in each figure.

The body A and base B are of the usual construction, the distinguishing feature of my

design being in the contour of the upper portion, which consists in having the same in the form of an ogee or cyma recta at each side, as clearly shown in Fig. 2, *c* indicating the concave, and *c'* the convex portions thereof. 25 The lower edge of said convex portions are finished with a molding, *m*, and the top *d* of the cover is flat, as in those ordinarily used.

What I claim is—

The design for a sewing-machine cover here- 30 in shown and described, in which the upper portion on each side is in the form of a cyma recta, as set forth.

In testimony that I claim the foregoing I have hereunto set my hand this 1st day of 35 December, 1883.

ALPHEUS W. MYERS.

Witnesses:

F. F. CAMPBELL.

OLIVER DRAKE.
